UNITED STATES PATENT OFFICE.

DAVID G. NOACK, OF CLEVELAND, OHIO.

GAGE-COCK.

SPECIFICATION forming part of Letters Patent No. 412,890, dated October 15, 1889.

Application filed April 25, 1889. Serial No. 308,615. (No model.)

To all whom it may concern:

Be it known that I, DAVID G. NOACK, a citizen of the United States, and a resident of Cleveland, county of Cuyahoga, and State of Ohio, have invented certain new and useful Improvements in Gage-Cocks, of which the following is a specification, the principle of the invention being herein explained and the best mode in which I have contemplated applying that principle, so as to distinguish it from other inventions.

My invention consists of the improvements hereinafter described and claimed.

Referring to the drawings, Figure 1 is a reverse plan view of the gage-cock. Fig. 2 is a central longitudinal section of the same, certain portions being in elevation. Fig. 3 is a detail face view of the inner portion of the recess of the modified form. Fig. 4 is a reverse plan view of the rotary packing-holder of the modified form. Fig. 5 is a longitudinal central section of the modified form. Fig. 6 is a side elevation view of the gage-cock in raised or open position. Fig. 7 is a detail view of the spindle and rotary packing-holder of the preferred form, showing the manner of locking the two together.

A is a nipple, screw-threaded at one extremity for attachment to the boiler and provided 30 at its forward extremity with the downwardly-inclining discharge-orifice a. At its upper portion are the lugs a', in which is pivoted the lug b, integral with the weight-lever B. Recess c is formed in the forward portion of of 35 said lever, and journaled transversely through the walls of said recess is the spindle d, having a thumb-button d' on its outer end. Spiral spring e is slipped over said spindle intermediate of said button and the side of the lever, while the opposite end of the lever is held 40 in position by pin e', said pin fitting and resting in the slots f, and thereby the spindle is prevented from turning, as the spring normally holds said pin in said slot. Rotary 45 packing-holder G is located within said recess and fits on said spindle, slot g engaging with lug g', which locks said packing-holder in rigid engagement with said spindle. A series of four cup-shaped disks h are formed 50 at regular intervals on said packing-holder, each of which disks is provided with a pe-

ripheral slot h'. Fitting in each disk is a rubber seat or packing j.

The operation is as follows: Let it be understood that one of the rubber disks or seats 55 is in engagement with the discharge-nipple, that the seat has become worn, and that it is desired to renew the same or bring a new seat into engagement with the discharge-nipple. Pressure is brought to bear on the thumb- 60 button d', thus compressing the spring and freeing the pin e' from engagement with the slot f. The rotary packing-holder may now be rotated a quarter-turn, which will bring a new seat j in position to come into contact with 65 the nipple, when the pin e' automatically catches in the slot f and retains the packing-holder in adjustment. As the worn-out seat is moved downwardly, the slot h' registers with the slot k on the lever. Any suitable instrument may be inserted to force out the rubber 70 seat, and a new seat may be fitted in its place without lifting the lever or in any way disturbing the adjustment of the gage-cock, or all four seats may be used one after the other 75 before any are renewed.

Referring to the modified form, Fig. 5, a spindle l is journaled longitudinally through the weighted lever. On its outer extremity the spindle is provided with a thumb-button 80 l', and its inner extremity is furnished with a saucer-shaped disk or rotary packing-holder m, in which fits seat m', that is secured in position by screw n. Spiral spring n' is slipped over the outer end of said spindle and has engagement at one extremity with the thumb-button and at its opposite extremity with the lever. Said spring serves to hold the ribs o, that are provided on the back of the rotary 85 packing, in engagement with the slots o' of the lever, and prevents the rotation of the packing, except when the spindle is pushed forward.

The operation of the modified form is as follows: Let it be understood that the portion of the packing in engagement with the nipple is 90 worn and it is desired to bring a fresh portion in engagement with the same. The button is pressed forward to free the lugs o from engagement with the slots o', and the spindle is then turned a sufficient distance to bring a 95 new and unused portion of the packing opposite the nipple. When the entire seat is worn,

the screw *n* is removed, new packing inserted in the packing-holder, and the screw replaced in position. As soon as lugs *o* are opposite slots *o'* and pressure is removed from the button, the pressure of the spring automatically causes said lugs to be drawn into said slots.

It will be noticed that in both the preferred form and the modified form the discharge-orifice *a* is inclined downwardly at such an angle that when the lever is raised any water discharged from said orifice will clear the rotary packing-holder.

The foregoing description and accompanying drawings set forth in detail mechanism in embodiment of my invention. Change may be made therein, provided the principles of construction respectively recited in the following claims are employed.

I therefore particularly point out and distinctly claim as my invention—

1. In a gage-cock, a rotary packing-holder provided with two or more independent removable seats, substantially as set forth.

2. In a gage-cock, the combination, with a rotary packing-holder, of a spindle engaging therewith, said spindle extending beyond the side of said gage-cock, whereby it may be turned, substantially as set forth.

3. In a gage-cock, the combination, with a rotary packing-holder, of a spring-pressed spindle engaging with said packing-holder, said spindle having a projecting portion, whereby it may be turned, and being spring-pressed, whereby it may be held in position, substantially as set forth.

4. In a gage-cock, the combination of a rotary packing-holder having one or more seats, a spindle having engagement therewith and provided with a thumb-nut, and a spring engaging with said spindle, substantially as set forth.

5. A gage-cock provided with a rotary nipple-engaging device having a series of faces located angularly to each other, substantially as set forth.

6. In a gage-cock, the combination, with a discharge-pipe, of a weight having pivotal engagement with said discharge-pipe and provided with a seat adapted to engage with said pipe, said discharge-pipe provided with a downwardly-inclining discharge-orifice, whereby as the weight is raised the issuing water will clear said seat, substantially as set forth.

7. In a gage-cock, the combination of a weight provided with a recess, a spindle pivoted in the walls of said recess, a rotary packing-holder provided with sockets secured to said spindle, seats fitting in said sockets, said spindle provided with a thumb-nut, whereby it may be turned, spring-locking mechanism that holds said packing-holder in stationary position, and a discharge-nipple to which said weight is journaled, substantially as set forth.

In testimony that I claim the foregoing to be my invention I have hereunto set my hand this 13th day of April, A. D. 1889.

DAVID G. NOACK.
